R. Balans,
Jib Sail Ring
N° 44,582. Patented Oct. 4, 1864.

Raymonde Balans

UNITED STATES PATENT OFFICE.

RAYMOND BALANS, OF PARIS, FRANCE.

IMPROVED JIB-SAIL RING.

Specification forming part of Letters Patent No. 44,582, dated October 4, 1864.

To all whom it may concern:

Be it known that I, RAYMOND BALANS, of No. 24 Rue de Dunkerque, Paris, in the Empire of France, gentleman, have invented certain new and useful Improvements in Jib-Sail Rings; and I do hereby declare that the following is a full and exact description thereof, reference being had to the accompanying drawing, and to the letters marked thereon.

My invention consists, first, in the application to jib-rings of a transversal roller dividing the circle into two parts; and, secondly, in the addition to the said rings of a holdfast-hook, by aid of which the sail can be bent with much greater ease and celerity than by the methods at present employed.

The accompanying drawing represents a ring comprising these improvements.

a a are two shoulder-pieces, formed one on each side of the inner circumference of an ordinary jib-ring, and serving as bearings to the axle shown by the dotted lines, on which is mounted a roller with hollow or concave surface *b b*. *c* is the holdfast-hook by which the ring is attached to the corresponding eyelet of the jib. *d* is a cheek-piece formed at each side of the ring, near the stalk of the hook, to serve as bearings for a square pivot, *e*, to which is fixed one end of the spring *ff*. The bar *g*, which traverses the two cheeks, by checking the expansion of this spring forces its free extremity to press against the point *h* of the hook, which is hollowed out for its reception. If so required, a hole may be drilled in this end of the spring corresponding with a stud set in the hollow of the hook, so as to prevent displacement.

The hook closed, as in the drawing, is opened at will by simple finger-pressure on the outer face of the spring, or (if of considerable size) by aid of a small chain or other pull-piece set near the head of the latter.

The spring may be made of either brass or steel, as desired; but in the larger sizes the former will generally be found most efficient, from its non-liability to oxidation.

It may here be remarked that the above mode of rendering hooks holdfasts may be adapted to hooks of all ordinary forms and dimensions in their several applications to general purposes.

Among the advantages resulting from the predescribed improvements may be noted, first, substitution of rolling to the sliding friction at present exercised on the rings and corresponding cordage in setting or lowering the sail, and consequent decrease in wear and tear; secondly, separation of the ropes in the same ring by the presence of the transversal roller, and consequent suppression of knotting or entanglement; thirdly, facility in setting or lowering of the sail, which can be effected by one-eighth of the force at present required; fourthly, facility and celerity in the bending of the sail, which operation can, by aid of the holdfast-hook, be readily performed even by landsmen.

Having now described the nature of my said invention and the manner of carrying it into effect, I declare that what I claim, and desire to secure by Letters Patent, is—

The application to jib-sail rings of a transversal roller, dividing the circle into two parts, and the addition to the said rings of a holdfast-hook corresponding with the eyelets by which the sail is secured thereto, the whole constructed in manner and for the purpose substantially as herein set forth, and represented in the annexed drawing.

RAYMOND BALANS.
